JOHN B. BRADFORD AND ARTHUR F. LEVITT, OF LOS ANGELES, CALIFORNIA.

WAVE-MOTOR.

1,324,335.

Specification of Letters Patent.

Patented Dec. 9, 1919.

Application filed July 1, 1918. Serial No. 242,760.

To all whom it may concern:

Be it known that we, JOHN B. BRADFORD and ARTHUR F. LEVITT, citizens of the United States, residing at Los Angeles, in the county of Los Angeles and State of California, have invented new and useful Improvements in Wave-Motors, of which the following is a specification.

Our invention relates to wave motors and consists in the novel features herein shown, described and claimed.

Figure 1 is a perspective of a wave motor embodying the principles of our invention.

Fig. 2 is a vertical sectional detail through the transverse center of the float and pier platform and taken on the line 2—2 of Fig. 3.

Fig. 3 is a horizontal sectional detail on the line 3—3 of Fig. 2.

20 The pier platform 1 is mounted upon piles 2 at the shore. The accumulator tank 3 is mounted upon the platform 1 and is provided with a valve controlled drain 4, a blow-off valve 5, and a pressure gage 6. A 25 pipe 7 leads from the bottom of the accumulator tank 3 to the water motor 8 and the water motor 8 is belted to a dynamo 9. The discharge pipe 10 from the water motor 8 leads downwardly through the platform 1 30 to return the water to the ocean.

The piles 2 are preferably arranged in sets of four, forming a rectangle in plan. Guide bars 11, 12, 13 and 14 are fixed upon the inner faces of the piles 2. A float 15 in the 35 form of a hollow flat boat is mounted between the guide bars 11 and 12, and between the guide bars 13 and 14, there being a central opening 16 vertically through the float. Channel plates 17 are fixed upon the corners 40 of the float at the upper side and at the lower side, there being an upper and lower channel plate for each of the guide bars 11, 12, 13 and 14 so as to hold the float 15 in position and allow it to move up and down 45 under the influence of the ocean waves. A lower bearing member 18 is mounted upon the float around the opening 16, a large bearing ball 19 seats downwardly upon this bearing member 18, an upper bearing member 20 is inserted downwardly to fit the ball 19, and the bearing members are connected together and to the float by bolts 21. A vertical bore 22 is formed through the bearing ball 19 and a pipe nipple 23 is screwed into 50 the lower end of the bore 22 and extends downwardly into the water. A neck 24 ex-

tends upwardly from the bearing ball 19, a bolting flange 25 is formed upon the neck, a disk 26 fits against the bolting flange 25, a pipe section 27 has a bolting flange 28 fitting 60 against the disk 26 in opposition to the flange 25, and bolts 29 secure the bolting flanges 25 and 28 together. A flat check valve 30 is constructed at the center of the disk 26 and opens upwardly.

65 An opening 31 is formed through the platform 1 in vertical alinement with the opening 16 in the float, an upper bearing member 32 is placed against the lower face of the platform around the opening 31, a bearing ball 33 is placed upwardly and seated in the bearing member 32, a bearing member 34 is placed upwardly around the bearing ball 33, and bolts 35 are inserted through the platform 1 and through the 70 bearing members 32 and 34 to hold the members together and to hold the bearing rigid with the platform. A vertical bore 36 is formed through the bearing ball 33, a pipe section 37 telescopes within the pipe section 80 27 and has a flange 38 bolted to the bearing ball 33 around the opening 36, and a flat check valve 39 is constructed at the lower end of the pipe section 37 and opens upwardly; so that as the float 15 falls, water 85 will pass upwardly through the check valve 30, and as the float rises the check valve 30 will close and hold the water and force it upwardly through the check valve 39 and continued action of the float will cause a 90 stream of water to flow upwardly through the opening 36.

A stuffing box construction 40 is formed upon the upper end of the pipe 27 around the pipe section 37, so that the pipe section 95 37 operates like a piston or plunger in the pipe 27.

A flexible pipe 41 has a flange 42 upon its lower end secured to the bearing ball 33 by bolts 43 and the upper end of the pipe 41 100 discharges into the accumulator tank 3.

The accumulator tank 3, when empty of water, is full of air, and air tight, and the operation of the float will pump water into the tank and compress the air, and the air 105 pressure will furnish a steady stream of water and water pressure through the pipe 7 to the water motor 8, thereby changing the unsteady motion of the float into the steady motion of the motor.

110 If it is desired to stop the water motor 8 the valve 44 in the drain 4 may be opened to

allow the water to run out of the tank as fast as it is pumped in, and the pressure and power may be regulated by manipulating this valve.

5 The bearing balls 19 and 33 in their mountings, together with the pipe 41, form a universally flexible connection between the float and the tank so as to allow the float to vibrate more or less in its travel up and 10 down.

10 The float 15 may be very large and the other parts correspondingly strong so as to furnish any desired amount of power.

15 Any desired machine may be driven from the water motor 8 instead of the dynamo 9 and electric power may be taken from the dynamo for any desired purpose.

20 Various changes may be made in the details of construction without departing from the spirit of our invention as claimed.

25 We claim:

1. A wave motor comprising four piles driven into the ground at a shore, a pier platform fixed upon the piles, guide bars attached to the inner faces of the piles and forming a vertical slideway, a float mounted to move up and down in the slideway, there being a central opening vertically through the float, a lower bearing member mounted 30 upon the float around the central opening, a large bearing ball fitting downwardly upon the lower bearing member, an upper member inserted downwardly to fit the ball, said bearing members being connected together 35 and to the float, there being a vertical bore through the bearing ball, a pipe nipple screwed into the lower end of the bore and extending downwardly, a neck extending upwardly from the bearing ball, a bolting

flange formed upon the neck, a disk fitting 40 against the bolting flange, a pipe section having a second bolting flange fitting against the disk, bolts connecting the bolting flanges together, a check valve construction upon the disk and opening upwardly, there being 45 an opening through the platform, an upper bearing member placed against the lower face of the platform around the opening, an upper bearing ball placed upwardly against the upper bearing member, a second bearing 50 member placed upwardly around the upper bearing ball, bolts inserted through the platform and through the bearing members, there being a vertical bore formed through the upper bearing ball, a second pipe section 55 telescoping within the first pipe section and having a flange bolted to the upper bearing ball, and a check valve in the second pipe section.

2. In a wave motor, a platform having an 60 opening, a float mounted to move up and down below the platform, there being a central opening vertically through the float, a pipe mounted in the opening in the float, means forming a ball and socket connection 65 between the pipe and the float, a second pipe telescoping in the first pipe, means forming a ball and socket connection between the second pipe and the platform, a flexible hose leading upwardly from the second pipe, and 70 check valves in the pipes so that as the float goes up and down water will be forced upwardly through the pipes.

In testimony whereof we have signed our names to this specification.

J. B. BRADFORD.
ARTHUR F. LEVITT.
